HEAT EXCHANGER

Gerhard Göbel, Darmstadt, Germany

Application October 5, 1951, Serial No. 249,997

1 Claim. (Cl. 257—138)

The present invention relates to heat exchangers of a new and improved design.

The heat exchanger according to the present invention is designed for highest efficiency from a technical as well as from an economic point of view, independently of whether the operating pressure difference is artificially created, as by fan action, or arises naturally from an updraft or a thermosyphonic action.

Generally speaking, the invention relates to a heat exchanger for flowing media having heat exchange surfaces comprising a plurality of flat bodies as main heat exchange elements, said bodies being arranged to form a substantially parallel grid and being spaced at small distances from each other to leave short gaps therebetween, said gaps being so dimensioned as to utilize the prevailing friction-pressure drop for optimum heat exchange.

In the drawings,

Fig. 1 is a cross section through a convactor on line 1—1 of Fig. 2, and

Fig. 2 shows a front view, partly in section along line 2—2 of Fig. 1.

According to the invention, the rear boundary of the diffusor adjacent to the heat exchange element may be a separate unit and may be movably arranged in such a way that in one position the shaft or duct above the heat exchange element is completely closed thereby; it can thus be used as a regulating element toward the atmosphere. By this movable rear wall, which may have an additional heat insulation, the heat radiation of the heating surface toward the fixed rear wall is largely absorbed and is transmitted to the air by convection. The front boundary of the diffusor can likewise be formed by a separate unit, which may form an evaporation vessel that can be tilted to the front or removed. After removal, an opening will be free for cleaning the inside.

The heat exchange element with adjacent diffusor, if desired, formed by the regulating flap and the evaporation vessel, may be a separate unit that can be built in by simple insertion and which does not require a separate design of the shaft. The assembly of these parts is very simple.

Referring now to the drawings in detail, numeral 33 designates hollow, horizontally arranged heat exchange bodies. The bodies have a wing-shaped profile and are exposed to the impact of the heating means at the inside.

The flat heat exchange bodies 33, together with the two lateral plates 49, the containers 59, which are provided with heating medium admission pipe 57, and discharge pipe 58, form the heat exchange element. This heat exchange element forms a complete unit with the short diffusor containing the regulating flap 37 and the evaporating vessel 35. The unit can also be used without the casing.

Due to the fan-shaped arrangement of the heat ex-

2

change bodies 33, the air current is likewise fan-shaped. The short diffusor is created by the curved walls of the evaporator 35 and the regulating flap 37. The highly accelerated air flow in the gaps between heat exchange bodies 33 is reconverted into pressure without essential loss, due to the diffusor action. The evaporating vessel 35 is supported at both ends by the angular member 46 on the projection 47 which is attached to the side plate 49. The vessel may be tilted on the pivot point 36, as indicated by broken lines 35' (Fig. 1). Evaporation of water contained in vessel 35 is enhanced by air circulation indicated at auxiliary inlet 60, which circulation is caused by the underpressure in the shaft. Numeral 37' indicates the regulating flap in closed position.

15 The regulating flap has counterbearings 40 which are open toward the bottom and are supported on edge-shaped bearings 38 mounted in the side walls. A flexible strap 41 provides a safe gasket in closed position. The counter-weight 42 and the proper position of the point of suspension provide a force-free action by means of a roller 39. The insulation of the double-walled regulating flap is designated by 43. The fixed front wall 44 of the shaft lining lies parallel to the rear wall. The baffle profiles 45 at the outlet are arranged in fan-shape 20 with decreasing deflecting angles toward the rear wall. In order to enlarge the exit opening, so as to decrease the energy at the outlet, it may be extended to the upper part of the front wall. It is advantageous for this purpose to have the horizontal exit plane merge in a rounded 25 contour 56 into the front wall in order to create favorable flow conditions. It is likewise advantageous to make the front boundary in the bottom part slope back to a point designated by 57' in the drawing. The front part of the evaporation vessel 35 may be provided with 30 a mask so that the heat exchange element with the diffusor can be used as a separate unit.

The evaporating vessel 35 is supported by angles 46 on projecting elements 47 which are joined by screws to lateral members 49.

35 40 The bent-back portions 50 of angles 46 prevent an automatic slipping-out of the evaporation vessel in the open position by engaging behind the projections 47.

45 While, in the foregoing, the heat exchange device according to the invention has been described and illustrated in a number of embodiments, it should be understood that the example given is by way of illustration only and that there are many modifications of the same possible without departing from the spirit of the invention.

50 Having thus described my invention, I claim:
A heat exchanger comprising in combination, a casing formed with a front wall, a rear wall, side walls and top, said front wall being provided with a primary air inlet; a convactor unit in said casing, said unit comprising a plurality of substantially flat parallel hollow streamlined fins defining internal passages for a conditioning medium and having turbine blade-like profiles the inner edges whereof define a concave surface from said primary air inlet, a humidifier adjustably pivotably disposed 55 in said front wall, above said primary inlet, pivot means for pivoting said humidifier in said front wall, an auxiliary air inlet in said front wall disposed above said humidifier and said convactor unit, a pivotable flap intermediate said rear wall and said parallel streamlined fins for regulating 60 the flow of air, pivot means in said wall for pivoting said flap, and an air outlet in said top of said casing.
